UNITED STATES PATENT OFFICE

163,994

AUTOMOBILE SERVICE RACK

John R. Fairweather, Collingswood, N. J.

Application November 22, 1950, Serial No. 13,090

Term of patent 14 years

(Cl. D52—2)

To all whom it may concern:

Be it known that I, John R. Fairweather, a citizen of the United States, residing at Collingswood, State of New Jersey, have invented a new, original, and ornamental Design for Automobile Service Rack, of which the following is a specification, reference being had to the accompanying drawing, forming a part hereof.

Figure 1 is a perspective view showing the automobile service rack.

Figure 2 is a perspective view showing the automobile service rack from a side opposite to that shown in Figure 1.

I claim:

The ornamental design for an automobile service rack as shown.

JOHN R. FAIRWEATHER.
